UNITED STATES PATENT OFFICE.

STOUGHTON L. WALKER AND JOHN M. LAURENSEN, OF JERSEY SHORE, PENNSYLVANIA.

COLLAPSIBLE CONTAINER.

1,346,731.

Specification of Letters Patent. Patented July 13, 1920.

Application filed January 24, 1920. Serial No. 353,673.

To all whom it may concern:

Be it known that we, STOUGHTON L. WALKER and JOHN M. LAURENSEN, citizens of the United States, residing at Jersey Shore, in the county of Lycoming and State of Pennsylvania, have invented new and useful Improvements in Collapsible Containers, of which the following is a specification.

10 Our invention relates to improvements in collapsible or knockdown boxes and the like, and more particularly to a type of the same adapted for shipment and reshipment by parcel post, express or freight.

15 Among other objects of the invention, it is desired, primarily, to provide a box or similar container constructed of relatively light weight materials, suitably reinforced at the edges and corners thereof, to withstand the usual rough and hard usage obtaining in the shipment of the same, and one capable of being collapsed into a relatively small and compact package, free from objectionable projecting edges and corners, 20 when collapsed, and presenting substantially broad flat top and bottom surfaces to permit a number of the same being assembled into packages or tiers for reshipment.

With the foregoing and other objects in view, the invention resides in the certain features of construction and arrangement of parts as will be hereinafter more fully described, set forth in the appended claims, and illustrated in the accompanying drawings, in which:

Figure 1 is a view, in perspective, of the invention when ready for shipment.

Fig. 2 is a longitudinal section thereof when collapsed, or ready for reshipment.

40 Fig. 3 is an end view of the box showing the overlap of the hinged corner strips of the side walls.

Fig. 4 is a transverse section of the box in collapsed condition.

45 Fig. 5 is a fragmentary longitudinal section of the box as in Fig. 1.

Fig. 6 is a transverse section on the line 6-6 of Fig. 5.

50 Fig. 7 is a fragmentary detailed interior view of a side and bottom wall and the hinge and interlocking connections between respective corner reinforcing strips.

Fig. 8 is an elevation of the inner face of one of the end wall reinforcing strips 55 showing the manner of hinging the side wall

and of interlocking the same in elevated position with the adjacent corner strip of a side wall.

Fig. 9 is a fragmentary detail showing the manner of securing the upper end of 60 the intermediate reinforcing strip of the side walls of the container.

Referring to the drawings, and the several views thereof, the box *per se* is formed to provide a bottom wall 1 having relatively 65 narrow side wall portions 2 and 3 secured to the opposite longitudinal edges thereof by means of nails, screws or the like, (not shown), the side wall portion 3 being of slightly greater width than the side wall 70 portion 2, as shown in Figs. 4 and 6; folding side walls 4 and 5 complementary to the side wall portions 2 and 3, respectively; end walls 7 and 8 slightly less in height than the combined height of the side walls 4 and 5 75 and their respective side wall portions 2 and 3; and a top wall or cover 9, the latter being of a length to rest upon the upper edges of the end walls and to have its upper surface lie flush with the top edges of the 80 side walls 4 and 5, when the end and side walls are in vertical or raised position.

The bottom wall 1 is provided at its opposite ends with reinforcing strips 10 and 11, each formed to provide horizontal flanges 85 12 adapted to be secured to the under face thereof, and vertical flanges 13 extending along the edges of the wall and projecting above the upper face of the latter. The vertical flanges 13 are of greater length than 90 that of the horizontal flanges 12, which are of a length coextensive with the width of the bottom wall, and have their opposite ends 14 bent around the adjacent edges of the side wall portions 2 and 3 and are suitably secured thereto. Secured between the flange portions 13 and 14 and the adjacent edges and faces of the bottom 1 and the side wall portions 2 and 3, at the corners thereof, are angular members 15 and 16, the former 100 corresponding in height to the side wall portion 2 and the latter to that of the side wall portion 3. Each pair of the angular members 15 and 16 are formed to provide transversely disposed hinge members 17 and 105 18, respectively, integral with the flanges thereof engaging the edges of the opposite ends of the bottom wall and the side wall portions carried by the latter.

The side walls 4 and 5 are each provided 110

at their opposite ends with corner reinforcing strips 19 and 20, respectively, each being formed substantially L-shaped in cross-section to provide flanges 21 and 22, the 5 former being secured on the outer faces of the walls and corresponding in length to the height of the same, while the latter project across the ends of the walls and beyond the inner faces thereof, and are prolonged at 10 their lower ends to provide hinge members 23 and 24 complementary to the hinge members 17 and 18 of the angular members 15 and 16, respectively. The hinge members 23 of the side wall 4 overlap the complementary hinge members 17 of the angular corner members 15, in contacting relation with the inner wall thereof, and are secured in such relation by means of rivets or the like 25, while the hinge members 24 of the 15 side wall 5 similarly overlap the complementary hinge members 18, of the angular corner members 16, but are disposed in contacting relation with the outer wall thereof, and secured in position by means of the 20 rivets 26.

The end walls 7 and 8 are each provided with pairs of reinforcing strips 27 and 28, respectively, secured in spaced relation on the outer faces thereof and having their 25 outer edges disposed flush with the side edges of the same. The lower ends of the strips 27 and 28 are provided with circular studs 29 projecting laterally therefrom and disposed in engagement with elongated slots 30 or recesses 30 formed in the opposed inner faces of the side wall portions 2 and 3, (see Figs. 7 and 8), the purpose of which arrangement will be hereinafter more fully described. The end walls 7 and 8 are retained in place between the side walls 4 and 5, when all of these walls are raised to vertical position, by means of tongue portions 31, formed in one edge of each of the strips 27 and 28, and which are adapted to interlock with the openings or recesses 32 formed in the flanges 22 of the angular corner members 19 and 20. Each of the strips 27 and 28 have their lower ends flush with the bottom edge of the end walls, but are of a 40 length admitting of their upper ends to project above the top edges thereof.

With the side and end walls in raised position and interlocked together by means of the tongues 31, engaging the recesses 32, the 45 top wall or cover 9 is placed in position between the side walls 4 and 5 with its opposite ends resting on the top edges of the end walls 7 and 8 and is held against longitudinal movement by means of the upwardly projecting ends of the strips 27 and 28. The top wall or cover 9 is reinforced along its opposite ends by means of transverse battens 33 which act to prevent the splitting or warping of the same. To secure the 50 top wall or cover 9 against accidental dis-

placement or removal, transversely extending cross-bars 34 are provided, the same being suitably spaced on the top face thereof and pivoted, as at 35, medially of their ends, and are adapted to be moved into and out 70 of engagement with slotted recesses 36 formed at suitable points in the top edges of the side walls 4 and 5. The top edges of the walls 4 and 5 are protected by means of reinforcing strips 37, of even length there- 75 with, and secured thereon by means of nails or other similar fastening means, and intermediate portions thereof serve as the top wall or closure for the slotted recesses 36 and for the retention of the adjacent ends 80 of the cross-bars 34 therein.

Depending upon the length of a container, constructed as hereinbefore described, it is contemplated to provide intermediate reinforcing strips for the side walls 85 (only being shown for each of the side walls 4 and 5 in Figs. 1 and 5 of the drawing) and the same consists of short strip sections 39 secured to the outer faces of the side wall portions 2 and 3, respectively, and 90 long strip sections 40 and 41 secured vertically of the side walls 4 and 5 and complementary to the sections 39 and having hinged connections respectively therewith, as indicated by the numerals 42 and 43. The upper ends of the long strip sections 40 and 41 are bent to provide end portions 44 which are adapted to seat in slight recesses formed in the top edges of the side walls immediately under the reinforcing strip 37, and secured in position by means of one of the fastening elements of the latter as shown in Fig. 9. The hinge connections 42 and 43 between the complementary strips project inwardly of coincidental slotted recesses, formed 105 in opposed edge portions of the complementary side wall sections, so as to lie in the plane of the corresponding hinge connections at the opposite ends of the latter.

With the container assembled in the manner as set forth in the foregoing description of its construction and arrangement, the same is to be collapsed for storage or shipment in the manner as shown in Figs. 2, 3 and 4 of the drawings, and to such end, the 115 cover is first unfastened by swinging the cross-bars 34 diagonally of the same and out of engagement with the recesses 36 and is removed. The end walls 7 and 8 are now to be unlocked by the disengaging of the 120 tongues 31 from the recesses 32, and this is accomplished by a sufficient upward movement of the end walls, such movement being permitted by reason of the play of the circular studs 29, of the reinforcing strips 27 125 and 28, in the vertically elongated slots, recesses or openings 32 of the side wall portions 2 and 3, until the tongues are free to be drawn through the recesses 32, after which the end walls are swung inwardly 130

and downwardly onto the upper surface of the bottom wall 1. The vertically sliding hinge connections of the end walls permit the latter to lie flat on the bottom wall, and this arrangement, together with the interlocking of the tongues 31 with the recesses 32 also attained through the same, constitute extremely important features of the invention. The top wall or cover 9 is now positioned upon the end walls 7 and 8 with its reinforcing strips 33 and cross-bars 34 uppermost so that its bottom surface lies flat upon the upper surfaces of the end walls, and after which, the side walls 4 and 5 are swung downwardly, in the order indicated, the former being supported upon the reinforcing strips 33 and the cross-bars 34 and the wall 5 flat upon the upper surface of the wall 4.

In the reverse manipulation of the several parts of the container, the side walls 4 and 5 are swung upwardly to vertical position, the cover 9 removed from its position on the end walls 7 and 8, and the latter swung upwardly to vertical position between the side walls 4 and 5 at the opposite ends thereof, and with a slight direct vertical movement, permitted by the hinge members 29 sliding in recesses 30, the tongues 31 are brought into alignment with the recesses 32 of the pairs of angular corner strips 19 and 20, and, by further outward swinging movement of the end walls, are passed through the recesses 32 and are then engaged over the bottom edge of the latter by a slight downward pressure on the end walls, thus holding the side and end walls in substantially interlocked position. The cover 9, after the container has been packed or filled with the desired contents to be shipped, is now placed in position and secured in the manner as hereinbefore described.

From the foregoing, it will be obvious that the invention provides for a simple and inexpensive container construction, the materials necessary for the several walls of the same being of minimum thickness and weight for a given size of the same, and by the application and arrangement of the several reinforcing strips and members a relatively strong, and with the interlocking features thereof, a substantially rigid construction is obtained.

It will also be obvious that, while the preferred form and features of construction and arrangement have been shown and described, it is within the scope of the invention to so modify such construction and arrangement as may be necessary for the manufacture of containers of varying size or shape, and increasing the number of the several reinforcing strips and interlocking members thereof accordingly with such variation of size and shape.

Having thus fully described our invention, what we claim is:

1. A collapsible container having a bottom wall, infolding end and side walls, and a removable cover wall, sliding hinge connections for the infolding end walls, reinforcing members for the several corners and edges of the container walls, and normally non-aligning interlocking means formed with adjacent corner reinforcing strips of the end and side walls, said interlocking means being operatively engaged for securing the end and side walls in vertical position by a vertical reverse directional movement of the end walls.

2. A collapsible container having a bottom wall, side wall portions secured to the longitudinal edges thereof, infolding side walls hingedly supported above said side wall portions, infolding end walls, and a removable cover wall, movable connections hingedly retaining the infolding end walls in position, reinforcing members for the several corners and edges of the container walls, and normally non-aligning interlocking means formed with adjacent corner reinforcing strips of the end and side walls, said interlocking means being operatively engaged for securing the end and side walls in vertical position by a vertical reverse directional movement of the end walls.

3. A collapsible container having a bottom wall, side wall portions secured to the longitudinal edges thereof, infolding side walls hingedly supported above said side wall portions, infolding end walls, and a removable cover wall, movable connections hingedly connecting the end walls and operating to permit the latter to normally lie in contacting relation with respect to the top surface of the bottom wall, reinforcing members for the several corners and edges of the container walls, and normally non-aligning interlocking means formed with adjacent corner reinforcing strips of the end and side walls, said interlocking means being operatively engaged for securing the end and side walls in vertical position by a vertical reverse directional movement of the end walls.

4. A collapsible container having a bottom wall, fixed side wall portions rising from the longitudinal edges thereof, infolding side walls hingedly supported above the fixed side wall portions, infolding end walls hingedly connected with the fixed side wall portions and arranged for a limited vertical movement with respect thereto, and a removable cover wall, reinforcing members for the several corners and edges of the container walls, and normally non-aligning interlocking means formed with adjacent corner reinforcing strips of the end and side walls, said interlocking means being opera-

tively engaged for securing the end and side walls in vertical position by a vertical reverse directional movement of the end walls.

5. A collapsible container having a bottom wall, fixed side wall portions rising from the longitudinal edges thereof, infolding side walls hingedly supported above the fixed side wall portions, infolding end walls hingedly connected with the fixed 10 side wall portions and arranged for a limited vertical movement with respect thereto, and a removable corner wall, reinforcing members for the several corners and edges of the container walls, normally non-aligning 15 interlocking means formed with adjacent corner reinforcing strips of the end and side walls, said interlocking means being operatively engaged for securing the end and side walls in vertical position by a vertical reverse directional movement of the end walls, and locking means for the cover wall.

6. A collapsible container having a bottom wall, fixed side wall portions rising

from the longitudinal edges thereof, infolding side walls rising above the fixed side wall portions, infolding end walls hingedly connected with the fixed side wall portions and arranged for a limited vertical movement with respect thereto, and removable 25 cover wall, reinforcing members for the several corners and edges of the container walls, certain of said reinforcing members being formed to provide hinge connections for the infolding side walls, normally non-aligning 30 interlocking means formed with adjacent corner reinforcing strips of the end and side walls, said interlocking means being operatively engaged for securing the end and side walls in vertical position by a 35 vertical reverse directional movement of the end walls, and locking means for the cover wall.

In testimony whereof we affix our signatures.

STOUGHTON L. WALKER.
JOHN M. LAURENSEN.
